GLOBE CLOCK STRUCTURE

Raymond R. Dupler, Toledo, Ohio

Application May 22, 1941, Serial No. 394,649

11 Claims. (Cl. 58—44)

This invention relates to globe clocks in which a globe has mechanism associated with it for indicating time.

An object of the invention is to produce an improved globe clock in which the time indicator is arranged inside of the globe and mechanism for operating the time indicator is located in the base or support for the globe.

Another object of the invention is to provide a globe clock with means to illuminate the inside of the globe and improved means to conduct energy to the illuminating means.

A further object of the invention is to provide a globe clock with the time indicating device inside the globe and the globe mounted for turning movement independently of the operation of the time indicator drive mechanism.

A still further object of the invention is to produce a globe clock of the above type in which the motor and driving mechanism for the clock are rotatable with the globe while being capable of driving the time indicator in proper synchronism irrespective of their positions of relative rotation.

Another object of the invention is to provide a time band supporting means in the form of integral lugs in one of the globe sections so that the operating mechanism is relieved of the load of supporting the time band and at the same time reduce the number of parts to a minimum.

Further objects and advantages will become apparent from a study of the following description when taken in connection with the accompanying drawing, in which

Figure 1 is a vertical sectional view of a globe clock incorporating the invention;

Figure 2 is a fragmentary detail view showing the motor and drive mechanism substantially at a right angle to the position shown in Figure 1; and

Figure 3 is a fragmentary detail view of the time band.

Referring to the drawing, the globe clock illustrated comprises a sphere 10 of glass or other transparent or translucent material formed in two parts fitting together in overlapping relation. When it is desired to use the sphere as a terrestrial globe, a map of the world may be displayed on the outer surface thereof in a suitable manner so that upon illumination of the globe from the inside, the outside will also be illuminated. The sphere 10 is mounted on a base 12 to which are connected wires 14 having a connecting plug 15 at the outer end. Switches 16 and 18 on the base 12 control a clock operating motor and a light source respectively.

The lower section of the sphere 10 is formed with an opening 20 which fits a projection on a block 21 of a spacing or mounting collar 22. The collar is rotatable in a recess 23 formed in the upper part of the base 12. To complete the sphere securing means a plate 24 having a projection fitting the opening 20 is secured to the block 21 from within the sphere by means such as screws 25. Thus the lower section of the globe is clamped between the collar 22 and plate 24 for rotation with the collar.

The inside of the base is hollow and extending through the upper wall thereof are a pair of telescoped tubes which pass through the center of the collar and into the sphere. The outer tube 27 is rotatable and has a plurality of upstanding arms 28 at its upper end to which is secured a time indicating band 30, a central ring 31 and spokes 32 between the band and ring being provided to transmit rotary movement to the band 30. The tube 27 is provided with a sleeve 34 which is threaded into an opening in the bottom of collar 22 and locked by screw 35 for rotation therewith. Depending from sleeve 34 are a pair of motor supporting brackets 37. The sleeve is provided with a collar 39 which abuts a washer 40 in engagement with the underside of the upper wall of the base to retain the sphere and its associated mechanism in assembled relation on the base while permitting rotation of the sphere.

The brackets 37 support a synchronous motor 42 of a type familiar to those skilled in the art, from which depends in effect a continuation of shaft 27 at 44 carrying three vertically spaced contact rings 45 to which are secured pick-up springs 46 engaging three concentric contact rings 47 mounted on an insulated plate 48 carried by the base. The rings 47 are suitably connected to the switches 16 and 18, as shown. The wires from the contact rings 45 extend upwardly to the motor 42 and a pair of such wires lead to a base 50 of a suitable type on which an electric lamp 51 is mounted, such wires passing through inner tube 52 on the upper end of which base 50 is mounted. Also mounted on the upper end of tube 52 is a wire bracket 54 which extends on both sides of the lamp and provides a support for a connecting device 55 which holds the two sections of the sphere 10 against separation. The connecting device extends through an opening in the upper section of the sphere in such manner that the bracket 54 is rotatable with the sphere.

Brackets 57 are provided respectively on the sleeve 34 and the motor 42 which support a split shaft 58 having a clutch 59 which connects the

shaft parts. A worm gear 60 is mounted on shaft 58 and is driven by a worm 61 on the armature shaft of the motor 42, while a gear 62 also on shaft 58 is in mesh with a gear 64 secured to the lower extremity of outer tube 27. Thus, the motor 42 drives the tube 27 through a suitable gear train to rotate the time band at its proper speed.

The collar 22 is provided with diametrically opposite recessed portions 66 slotted at 67. Adjacent the slots and projecting therethrough is a knurled time reset wheel 68 fixed to tube 27 to rotate the latter, clutch 59 being arranged to slip to permit "setting" of the time band independently of the motor and drive gearing.

The lower section of the sphere is provided with a plurality of spaced lugs 70 to support the time band 30 for rotation with respect thereto. The arrangement of lugs 70 is such that the time band rests thereon to take the load off the driving mechanism, and thus the tube 27 need serve only to rotate the time band. This is desirable, for example, when the globe is made of glass as the lugs may be formed as integral parts of the lower section, additional supporting structure for the time band being unnecessary. At the same time, the openings at the north and south poles of the sphere are provided only for the connecting means for the two globe sections, as no other openings are required for a supporting structure, for the time band.

The band 30 comprises an annulus or ring of glass or other suitable translucent or transparent material and is calibrated as shown in Figure 3 as at 72, numbers and other indicia designating the time. It will be apparent that when the lamp 51 is energized, the indicia 72 will be visible from the outside of the globe.

From the above it will be apparent that the motor 42 imparts turning movement to the time band 30, independently of the position of the sphere with respect to the base, and that rotation of the sphere on the base carries the motor with it without interruption of the current flow to the motor and lamp due to the contact ring arrangement. Thus, it will be seen that a simple arrangement has been provided which enables the globe to be used in the usual manner, and at the same time provides a clock, the operation of which is not hampered by the use of the structure as a globe.

Numerous changes in details of construction, arrangement and operation may be effected without departing from the spirit of the invention, especially as defined in the appended claims.

What I claim is:

1. A globe clock comprising a base, a sphere mounted on said base for turning movement with respect thereto, a time indicating band within said sphere rotatable relative thereto, a lamp within the sphere for rendering the time band visible from the outside of the sphere, and clock mechanism in said base and rotatable with said sphere for driving said time band irrespective of relative positions of rotation between said time band and sphere.

2. A clock comprising a terrestrial globe having translucent walls, a translucent time indicating band within said globe having indicia for designating the time, a stationary base on which said globe is rotatable, an electric clock mechanism within the base for rotating said time band, said clock mechanism being mounted for rotation with said globe, and means for energizing said clock mechanism including relatively rotatable contact

elements between said base and clock mechanism.

3. A clock comprising a base, a translucent globe mounted on said base for turning movements, a pair of telescoped tubes projecting inside of said globe, a time band mounted on one of said tubes for rotation therewith, a lamp within said globe and mounted on the other of said tubes, and an electric clock mechanism within said base and having a gearing connection with the first of said tubes for turning the latter.

4. A clock comprising a base, a globe mounted on said base for turning movements, a tube projecting inside of said globe, a time band mounted on said tube, a motor in said base, gearing between said motor and said tube, and means for turning said tube independently of said motor including a knurled hand wheel on said tube and a slip clutch interposed in said gearing.

5. A clock comprising a base, a globe mounted on said base for turning movements, a pair of telescoped tubes projecting inside of said globe, a time band mounted on one of said tubes for turning movement therewith, clock mechanism for turning said tube, a lamp mounted on the other of said tubes, and lead wires connected to said lamp passing through said latter tube.

6. A globe clock comprising a base, a sphere mounted on said base for turning movements, a time band in said sphere, a clock motor in said base for rotating said time band, said motor and sphere being clamped together with a portion of the base therebetween and turnable independently of the rotation of said time band, and means for rendering said time band visible through said sphere.

7. A globe clock comprising a base, a translucent sphere mounted on said base for turning movements, a time band within said sphere, a tube projecting inside of said sphere and arranged to rotate said time band, a sleeve surrounding the lower end of said tube and connected to said sphere for turning movement therewith, a motor carried by said sleeve and geared to said tube for rotating the tube, and means to energize said motor to rotate said time band irrespective of turning movement of said sphere and motor.

8. A globe clock provided with a base having a motor mounted therein, comprising a translucent sphere made up of two sections, a time indicating band within said sphere, a plurality of spaced lugs formed on the inner wall of one of said sections for supporting said time band for turning movements, a tube inside of said sphere having an end connected to said time band, the other end of said tube extending into said base and geared to the motor, a second tube within the first mentioned tube, and a lamp supported on said second tube inside of said sphere for rendering said time band visible through said sphere.

9. A terrestrial globe clock comprising a base, a motor in said base, a translucent sphere mounted for rotation on said base, a source of light in said sphere, said light source being mounted on a tube extending into said sphere, a second tube surrounding said tube and geared for rotation by said motor, a time band rotatable with said second tube, and means formed in the wall of said sphere for supporting said time band for rotation.

10. A clock comprising a base, a sectional globe mounted on said base for turning movements, a tube projecting inside of said globe, a time band

connected to said tube for turning movement therewith, means formed integral with a globe section for supporting said time band, and clock mechanism in said base for turning said tube.

11. A clock comprising a base, a globe mounted on said base for turning movements, said globe being formed of upper and lower sections, a tube

projecting inside of said globe, a time band connected to said tube for turning movements therewith, a plurality of spaced lugs formed in the wall of said lower section for supporting said time band, and clock mechanism for turning said tube and time band.

RAYMOND R. DUPLER.
